Thomas Edward King,

By Macdonald & Macdonald,

Attorney

UNITED STATES PATENT OFFICE.

THOMAS EDWARD KING, OF WESTFIELD, NEW JERSEY, ASSIGNOR TO HITCHINGS & COMPANY, OF ELIZABETH, NEW JERSEY, A CORPORATION OF NEW JERSEY.

CLOSURE FOR POWER DEVICES.

Application filed June 2, 1925. Serial No. 34,383.

This invention relates to a closure for a power device embodying a gearing and has been especially designed for use in connection with the transom operating mechanism disclosed in my copending application, Serial No. 34,384.

An important object of the invention is to provide a closure or housing for a manually operated worm gearing and its rotatable spindles.

A further object lies in the provision of means for concealing the wedge connection between the spindle of said worm gearing and a crank.

A still further object resides in the construction of a spring-pressed closure which may be retracted to expose certain connecting parts during the assembling or disassembling of the mechanism contained in the housing.

Another object is to provide a housing of this character which will be simple and inexpensive to manufacture, admit of ease and economy in assembling together with several parts of mechanism.

My invention consists in various novel constructions and combinations of parts, all as hereinafter described and particularly pointed out in the appended claims; and will be readily understood by reference to the accompanying drawings, which form part of this specification.

In said drawings:

Fig. 1 is a front elevation of a housing. Fig. 2 is a side elevation of a housing and its component parts, or more specifically, as it appears when connected to a transom operating mechanism.

Fig. 3 is a horizontal sectional view taken through the major axis of said housing, substantially on the line 3—3 of Fig. 1; and

Fig. 4 is a vertical sectional view of the housing on the line 4—4 of Fig. 1, the component parts of the mechanism being shown in the position indicated in Fig. 2.

As hereinbefore pointed out, I have designed this housing with special reference to a transom operating mechanism, such as find common use in dwellings, office-buildings and hotels, where a neat and compact device is favorably received. Its limitations, of course, are not to be restricted to this use solely, as obviously my invention will be

found extremely useful in the large field of mechanics wherein a simple and inexpensive means for inclosing a gearing is required.

On inspection of the drawings it will be observed that the main body portion 5 is substantially elliptical in form and consists of a face 6 and a marginal flange 7, which define a relatively deep chamber 8, as best shown in Fig. 3. The rear of the housing is left open for the insertion of the gearing as will be more specifically pointed out hereinafter.

As shown in Fig. 1 the housing 5 is provided with an upstanding extension 9, which is apertured, as indicated at 10, for the reception of a rotatable shaft of a transom operating device. This extension is rounded over in front, blending into the face and flange of the body portion to present a neat and artistic appearance, while the sides and top thereof continue straight to the rear.

Arranged eccentrically with the minor axis of the housing is a forwardly directed annular flange 11, having a centrally apertured partition 12 at the base thereof, said partition being substantially on a plane with the face 6. The aperture in the partition 12 is designated by the numeral 13, and disposed radially thereof are smaller apertures 14 and 15, preferably positioned as indicated in Fig. 1.

In assembling the various parts, the gearing inclosed in a special casing 16, is inserted by the rear of the housing and the hub extension 17, containing and furnishing a bearing for the spindle 18, enters the aperture 13, and is centrally positioned therein by inserting the pins 19 and 20, of said casing 16, into the apertures 14 and 15 respectively. As clearly illustrated in Fig. 4, the casing 16 bears against the rear face of the partition 12 while the vertical spindle 21 is alined with the aperture 10 and in position for connection with the shaft of the transom operating device.

I now direct particular attention to a novel closure means which I have adopted for closing the space within the annular flange 11, and as this feature is perhaps more clearly shown in Fig. 4, the balance of the description may be read on same.

The numeral 22 denotes a closure, formed as illustrated, its rear being slightly bent

inwardly to form a bearing portion 23, which operates within the flange 11, while its front end is reduced in diameter and bent upon itself, as indicated at 24.

- 5 The gearing casing 16 being now positioned within the housing 5, the closure 22 is next placed within the space within the annular flange 11, and is depressed to practically contact with the partition 12 to expose alined apertures 25 and 26 in the crank 27 and spindle 28. A wedge pin 29 is then inserted in said apertures 25 and 26 firmly connecting the crank and spindle 28. A coiled spring 30, previously placed within 10 the closure 22, constantly urges the latter to advance and when released the front end of said closure abuts the shoulder 27² of said crank, said forward movement positioning the component parts as indicated in Fig. 4, 15 and it will be noted that sufficient clearance is provided between the rear of the closure 22 and the partition 12, so the former may be depressed against the latter to expose the pin 29 when it is desired to disassemble the 20 parts.

In order to reduce the number of exposed screw heads I prefer to provide openings 31 in the partition 12, which are adapted to receive screws for attaching the housing to a support. Obviously these screws must be inserted before the closure 22 is affixed. The housing may be further provided with an opening 32 to receive an attaching screw if desired.

35 There are many minor changes and alterations that can be made within my invention, and I would therefore have it understood that I do not limit myself to the exact construction herein shown and described, but 40 claim all that falls fairly within the spirit of the invention and the scope of the claims.

I claim:

1. A device of the character described comprising a housing inclosing a gearing connected to a spindle, and having an aperture at the top thereof to receive a shaft,

a front extension in the face thereof, an apertured partition at the rear of said extension and a spring-pressed closure arranged within said front extension, said closure concealing the connection between the spindle of said gearing and an operating crank. 50

2. A device of the character described comprising an elliptical housing inclosing a gearing connected to a spindle, an upwardly directed apertured extension adapted to receive a shaft, a front extension in the face thereof, an apertured partition at the rear of said extension, and a spring-pressed closure arranged within said front extension, said closure concealing the connection between the spindle of said gearing and an operating crank. 55

3. A device of the character described comprising an elliptical housing inclosing a gearing connected to a spindle, an upwardly directed apertured extension adapted to receive a shaft, a front extension in the face thereof, an apertured partition at the rear of said extension and defining a shallow chamber, a closure slidably arranged within said chamber and a coiled spring positioned therein urging the same forward to conceal the connection between the spindle of said gearing and an operating crank. 60

4. A device of the character described comprising a flanged elliptical body inclosing a gearing connected to a spindle, an upwardly directed apertured extension adapted to receive a shaft, a front extension arranged eccentric to the minor axis of said body having an inwardly directed flange, an apertured annular partition spaced rearwardly from said flange and defining a shallow chamber, a closure slidably arranged within said chamber and a coiled spring positioned therein, urging the same forward to conceal the connection between the spindle of said gearing and an operating crank. 65 70 75 80 85

T. EDWARD KING.
